UNITED STATES PATENT OFFICE.

WILLIAM B. MURRAY, OF DANVILLE, ILLINOIS, ASSIGNOR TO THE MILLER TRAIN CONTROL CORPORATION, OF STAUNTON, VIRGINIA, A CORPORATION OF VIRGINIA.

TRAIN-CONTROL SYSTEM.

1,294,823.

Specification of Letters Patent. Patented Feb. 18, 1919.

Application filed March 16, 1914. Serial No. 824,984.

To all whom it may concern:

Be it known that I, WILLIAM B. MURRAY, a citizen of the United States, residing at Danville, in the county of Vermilion and 5 State of Illinois, have invented certain new and useful Improvements in Train-Control Systems, of which the following is a specification.

My invention relates to train control systems of the general type wherein the track is divided into blocks of suitable length, there being means to stop and signal the locomotive, car or other vehicle traveling upon the track, upon the same approaching the 10 entrance end of each block, and has particular reference to means of this character, wherein the locomotive, car or other vehicle is equipped with a plurality of independently operating preferably fluid pressure 15 operating apparatuses, for actuating train stopping means and signaling means respectively, each apparatus being mechanically set into action by ramp or ramp-sections guarding the entrance end of each 20 block, there being electrically operated means to render each apparatus inoperative or operative with respect to fulfilling its function, in accordance with track conditions.

30 An important object of the invention is to provide means of the above mentioned character, wherein independently operating train stopping and signaling apparatuses are employed, whereby upon the failure of 35 one to operate, the other will operate.

A further object of the invention is to provide a convenient and reliable operative connection between the mechanically actuated shoe carrying element, which is moved 40 by engagement with the ramp, and the train stopping or signaling apparatus.

45 A further object of the invention is to provide apparatus of the above mentioned character, which is comparatively simple in construction, inexpensive to manufacture, reliable in operation, strong and durable.

Other objects and advantages of this invention will be apparent during the course of the following description.

50 In the accompanying drawings forming a part of this specification and in which like numerals are employed to designate like parts throughout the same,

Figure 1 is a diagrammatic view of the track circuit and associated elements, 55

Fig. 2 is an enlarged side elevation of one of the ramps employed to guard the entrance end of each block,

Fig. 3 is a plan view of a pair of ramps guarding the entrance end of each block, 60

Fig. 4 is a side elevation of the rear portion of the locomotive, showing the same equipped with my apparatus,

Fig. 5 is an edge elevation of the mechanically operated contact or shoe carrying element, 65

Fig. 6 is an enlarged sectional view taken on line 6-6 of Fig. 7,

Fig. 7 is a sectional view taken on line 7-7 of Fig. 5, 70

Fig. 8 is a side elevation of electrically operated means for rendering the mechanically operated means operative and inoperative with respect to actuating the train stopping means, 75

Fig. 9 is a sectional view taken on line 9-9 of Fig. 8,

Fig. 10 is a side elevation, taken in the engine cab, of fluid pressure operated means for actuating the throttle lever and engineer's air brake valve, and, 80

Fig. 11 is a plan view of the throttle lever and operating means therefor.

Attention being called first to Fig. 1, the numerals 15 and 16 designate traffic rails, 85 insulated at intervals, as shown at 17, for providing blocks A, B, C, and D, of suitable length. The traffic upon the track is in one direction, as indicated by the arrows.

Each block is provided with a local track 90 circuit, comprising a source of current 18, preferably arranged near the exit end thereof, as shown. This source of current has one pole thereof connected with a wire 19, which is connected with the traffic rail 15, 95

The opposite pole of the source of current is connected with a wire 20 having connection with the traffic rail 16. Arranged preferably near the entrance end of each block is an electro-magnet or electrically operated 100 device 21, having one end of its winding connected with the traffic rail 15 by means of a wire 22, the opposite end of such winding being connected with the traffic rail 16 by a wire 23. The electro-magnet 21 is in- 105

cluded in a relay for controlling the elec-

trical connection with ramps or ramp-sections and a source of current, as will be fully explained.

Arranged suitably near and in advance of the entrance end of each block are ramps 24 and 25, which are curved longitudinally upwardly in a substantially vertical plane. These ramps are preferably from 80 to 100 feet long, and in some instances considerably longer. The ramp 24 is formed in two ramp-sections 24^a and 24^b, insulated as shown at 26. The ramp 25 is formed in two ramp-sections 25^a and 25^b, insulated as shown at 27. These ramps are held stationary in their proper positions by any suitable means.

Preferably arranged near the exit end of each block is a source of current 28, having one of its poles electrically connected with the traffic rail 16 of the adjacent rear block, as shown. The opposite pole of the source of current is connected with a wire 29, which is connected with the ramp-sections 24^b and 25^b. It is thus seen that the ramp-sections 24^b and 25^b have permanent electrical connection with one pole of the source of current 28, for a purpose to be more fully explained. Connected with the wire 29 is a contact-armature 30, adapted to coöperate with a stationary contact 31, connected with a wire 32. When the electro-magnet 21 is energized, the contact-armature is swung into engagement with the stationary contact 31, but when the electro-magnet is deenergized the contact-armature 30 automatically disengages the contact 31. The wire 32 is connected with a contact or pivot 33, arranged near a coöperating stationary contact 34, connected with a wire 35, in turn connected with a wire 36, which is connected with the ramp-section 24^a. 36' and 37' designate spaced stationary contacts, arranged in alignment with the contact 33. The contact 36' is connected with a wire 38', having connection with the ramp-section 25^a, while the wire 35 is also connected with the contact 37'.

Arranged suitably near the entrance end of each block is a signal or semaphore paddle 36, adapted to assume three positions, to wit, an uppermost position for indicating a clear block, an intermediate position for indicating caution condition, and a lowermost position for indicating danger or stop condition. Any suitable means may be employed to shift or move the semaphore paddle, the same forming no part of my invention, for which reason it is thought unnecessary to show them. For the sake of illustration, I have shown block B as being clear, block C as being at caution condition, and block D at danger condition, the semaphore paddles 36 assuming the three positions, for indicating the block conditions, as above explained.

Connected with each of the contacts or pivots 33 is a vertically swinging contact blade 37, adapted to assume three positions, to wit, an uppermost position to disengage contact 34 and simultaneously engage contacts 36' and 37', an intermediate position to disengage contacts 36' and 37' and engage contact 34, and a lowermost position to disengage all of the contacts 34, 36' and 37'. The contact blade 37 is extended laterally beyond the pivot 33 for affording a crank, to which is pivotally connected an upwardly extending operating rod 38, pivotally connected with a crank 39, extending laterally beyond a pivot 40 of the semaphore paddle. It is thus seen that the contact blade 37 will be swung with the semaphore paddle to assume corresponding positions with relation thereto.

The numeral 41 designates, as a whole, 85 mechanically operated apparatus for actuating train stopping means and the numeral 42 designates, as a whole, mechanically operated apparatus for actuating signal means. These mechanically operated apparatuses 90 are identical whereby a detail description of one will answer for both. Each apparatus 41 and 42 (see more particularly Figs. 4, 5, 6 and 7), comprises a vertical member or support 43, rigidly attached to the frame 95 work of the locomotive, preferably in advance of the driving wheels thereof. The vertical support 43 is provided near its lower end with a tubular guide or casing 43', for receiving a reciprocatory element or bar 44. 100 Rigidly connected and thoroughly insulated from the lower end of the reciprocatory bar or element 44 is a contact carrying shoe 45, which, as more clearly shown in Figs. 6 and 7, is provided upon its lower engaging face 105 with a recess 46, receiving a contact 47, pivoted within the recess, as shown at 48. The contact 47 is moved or urged outwardly by a suitably stiff compressible coil spring 49, such outward movement of the contact being 110 positively limited by a stop lug or extension 50, operating within a curved groove 51, contiguous with one end of the recess 46, as shown. The reciprocatory element or bar 44 is moved or urged downwardly by a compressible coil spring 52, surrounding the same, and engaging at its upper end with an apertured fixed arm 53, and at its lower end, a stop pin 54, carried by the bar or element 44 and engaging the upper end of the tubular guide 43', to positively limit the downward movement of the bar or element. At this point it is thought advisable to call attention to the fact that the reciprocatory elements or bars 44 are arranged side by each 115 in transverse alignment, the element or bar 44 included in the apparatus 41 being arranged inwardly of the element or bar 44 included in the apparatus 42, whereby the shoe 45 of the apparatus 41 will engage with 120 the shoe 45 of the apparatus 42. At this point it is thought advisable to call attention to the fact that the reciprocatory elements or bars 44 are arranged side by each 125 in transverse alignment, the element or bar 44 included in the apparatus 41 being arranged inwardly of the element or bar 44 included in the apparatus 42, whereby the shoe 45 of the apparatus 41 will engage with 130

and be moved by the ramp 24, while the shoe 45 of the apparatus 42 will engage with and be moved by the ramp 25, as will be more fully explained. Each apparatus 41 and 42 5 comprises fluid pressure operated connecting means 55, more clearly shown in Fig. 4. Such connecting means comprises a primary diaphragm shell or casing 56, preferably formed in upper and lower parts 57 and 58, 10 which are bolted or otherwise rigidly connected, as shown at 59. Arranged within the diaphragm shell or casing is a flexible diaphragm 60, having its edges confined between the adjacent flanges or edges of the 15 parts 57 and 58. This diaphragm is preferably formed of leather or any other suitable material. Connected with the diaphragm 58 is a depending rod 61, mounted to reciprocate within an opening, formed 20 through the lower part 58 of the diaphragm shell or casing. The rod 61 is arranged permanently in the path of travel of a head 67 preferably formed upon the upper end of the bar or element 44, to be elevated thereby 25 upon the upward movement of the latter. Arranged preferably near or within the cab of the locomotive is a secondary diaphragm shell or casing 68, preferably substantially identical with the primary diaphragm shell 30 or casing 56. Arranged within the diaphragm shell or casing 68 is a flexible diaphragm 69 formed of leather or other suitable material. Leading into the diaphragm shell or casing 68, below the diaphragm 69, 35 is a conduit 70, which leads into the primary diaphragm shell or casing 56, above the diaphragm 60. The diaphragm shell or casing 68, below the diaphragm 69, is suitably filled with a fluid, also filling the conduit 70, and the diaphragm shell or casing 56, above the diaphragm 60. This fluid may 40 be air, alcohol, oil, or in fact any gas or liquid which will not readily freeze.

As more clearly shown in Figs. 4, 8 and 9, 45 the numeral 71 designates a rod which is attached to the diaphragm 69, and extends upwardly through and beyond the diaphragm shell or casing 68.

This rod 71 is connected with electrically 50 operated means, designated as a whole by the numeral 72, for rendering the mechanically operated apparatus operative and inoperative with respect to operating the train stopping means or signaling means. These 55 electrically operated means, as more clearly shown in Figs. 8 and 9, comprises a stationary casing 73, preferably arranged near or within the cab of the locomotive, and held stationary by any suitable means. Fixed to 60 the floor or bottom of the casing 73 are spaced arms or bearings 74, apertured for receiving a horizontal shaft 75. Pivotaly mounted upon this horizontal shaft is an inner sleeve or tubular element 76, having a 65 laterally extending crank 77, rigidly con-

nected and preferably formed integral therewith. This crank has its outer end pivotally connected with the upper end of the rod 71, as shown at 78. Pivotaly mounted upon the inner sleeve 76 is an outer sleeve or 70 tubular element 79, having an opening 80 formed therethrough, for receiving a depending bolt 81. This bolt is adapted for movement into and out of a curved opening or groove 82, formed in the inner sleeve 76, 75 and when within the groove, the same serves to lock the sleeves 76 and 79 together, whereby a turning movement of the sleeve 76 will effect a corresponding turning movement of the sleeve 79, but when the bolt is withdrawn 80 from the groove, the sleeve 76 is free to turn without effecting a corresponding movement of the sleeve 79. Rigidly connected and 85 preferably cast integral with the outer sleeve 79 is an upwardly extending electro-magnet support or arm 83, upon which is rigidly mounted a vertically arranged electro-magnet 84, preferably inclosed within a non-magnetic casing. The electro-magnet, when energized, swings its armature 85 upwardly, 90 such armature having the bolt 81 rigidly attached thereto. The armature 85 has one end thereof pivoted with a knuckle 86, rigidly attached to the support 83. It is thus 95 seen that when the electro-magnet 84 is de-energized the sleeves 76 and 79 will be locked, to move together, but when the electro-magnet is energized, the turning movement of the sleeve 76 will not be transmitted to the sleeve 79. The electro-magnet 84 has 100 one end of its winding connected with a wire 84' which is electrically connected with the shoe 45, while the other end of the winding of this electro-magnet is connected with a wire 85' which is grounded to the frame 105 work of the locomotive. The construction of this electrically operated means is identical with the electrically operated means shown in my co-pending application for 110 train control system, filed February 10, 1913, Serial No. 747,498, wherein the same is fully disclosed in view of which it is thought that no further showing of the same is necessary in this application, such means not being 115 claimed *per se* in this application.

Arranged within each of the casings 73 is a valve structure 87, of any well known or preferred type. Each of these valve structures is operated by a depending crank 88, pivotally connected with the support 83 120 through the medium of a pitman or link 89, as shown.

The valve structure 87 in the apparatus 41 is connected in or with a pressure supply pipe 90, leading to the main reservoir 91 of the air brake system. The valve structure 87 of the apparatus 42 is connected in or with a pipe 92, connected with the pipe 90 by a T coupling 93.

Connected with the valve structure 87 of 130

the apparatus 41 is a pipe 94, which, as more clearly shown in Figs. 10 and 11, leads into the intake end of a throttle lever operating cylinder 95. This cylinder is pivotally attached to the face of the boiler by a bolt 96 or the like. This cylinder is preferably provided with a small or pin hole exhaust 97, whereby pressure within the cylinder may exhaust therefrom, upon the cutting off of the supply of pressure from the same. Mounted to reciprocate within the cylinder 95 is a piston 98, connected with a piston rod 99, which extends outwardly beyond the cylinder 95. This piston rod has its free end 10 suitably pivotally connected, as shown at 100, with one arm of a bell-crank lever 101, pivoted at 102, to a bracket or support 103. The outer arm of the bell-crank lever 101 is pivoted at 104 with a link or element 105, 15 which traverses a throttle lever 106, and is provided with laterally extending lugs or trunnions 107 and 108, which are normally spaced from and out of engagement with the throttle lever, said throttle lever being disposed between and in the path of travel of the same. The outer end of the link 105 is pivotally connected with one end of a bell-crank lever 109, pivotally connected with the throttle lever 106, as shown at 110. The bell-crank lever 109 is urged in one direction by a retractile coil spring 111. Extending longitudinally of the throttle lever is the usual latch rod 112, serving to operate a latch 113, to engage with a stationary toothed quadrant 114, such latch being forced inwardly toward the quadrant by a spring 115. The rod 112 is connected with a bell-crank lever 109 through the medium of a link 116. The latch rod 112 is connected with a hand grip 117, to be manually operated thereby. Pivotally connected with the throttle lever, as shown at 118, is a link 119, operating the throttle valve through the medium of a throttle valve stem 120, with which the same is pivotally connected.

Connected with the pipe 90, through the medium of a T-coupling 121, is a pipe 122, discharging into the inlet end of a preferably horizontally arranged cylinder 123, held stationary within the locomotive cab by any suitable means. The cylinder 123 is provided with a small or pin hole exhaust port, (not shown) identical with the exhaust means 97 of cylinder 95, whereby pressure contained therein after the supply of the same has been cut off may gradually exhaust to the atmosphere. Mounted to reciprocate within the cylinder 123 is a piston 125, connected with a rod 126, having pivotal connection with the lever of an engineer's air brake valve 127, of any well known or preferred type.

The valve 87 of the apparatus 42 is connected with a pipe 128, having connection

with a whistle or audible signal device 129, as shown.

The operation of the apparatus is as follows:—

In accordance with the illustration in Fig. 1, it is assumed that the block D is occupied by a train, whereby the semaphore paddle guarding the entrance end of the block D is at danger or stop, the semaphore paddle guarding the entrance end of block C at caution, and the semaphore paddle guarding the entrance end of the block B at clear. Assuming that a locomotive or train is traveling from block A into block B, then when the same moves into proximity to the ramps 24 and 25, near the entrance end of block B, the contact 47 and shoe 45 of the apparatus 41 will engage ramp-section 24^a, while the contact 47 and shoe 45 of the apparatus 42 will engage the ramp-section 25^a. The shoes 45 and reciprocatory elements or bars 44 connected therewith are thus gradually elevated. Prior to this upward movement of the rod or element 44, of the apparatus 41, a circuit is closed for energizing the electro-magnet 84 of such apparatus, whereby the bolt 81 is withdrawn from the groove 82 and the sleeves 76 and 79 unlocked, the turning movement of the sleeve 76 not being transmitted to the sleeve 79. In the absence of a locomotive or vehicle in the block B such block being clear, there is a closed track circuit including the electro-magnet 21, whereby the contact-armature 30 engages the contact 31. In the closed track circuit for energizing the electro-magnet 21, current flows from one pole of the source of current 18, through wire 20, traffic rail 16, of block b, wire 23, electro-magnet 21, wire 22, traffic rail 15, and through wire 19 back to the opposite pole of the source of current. In the closed circuit for energizing the electro-magnet 84 of the apparatus 41, current flows from one pole of the source of current 28 adjacent the entrance end of block B, through contact-armature 30, contact 31, wire 32, contact blade 37, contact 37', (the contact blade 37 now engaging the contact 37', since the semaphore paddle 36 is in the uppermost position), through wire 35, ramp-section 24^a, contact 47 and shoe 45, wire 85', electro-magnet 84, wire 84', the frame work of the engine, traffic rail 16 of block A, and back to the opposite pole of the source of current. Upon the upward movement of the element or bar 44 of apparatus 41, the upper end thereof engages the lower end of the rod 61, such movement being transmitted through the medium of the fluid pressure operating connecting means including the diaphragms, to the rod 71, which is accordingly elevated. This movement of the rod 71 will swing the crank 77 upwardly. This swinging movement of the crank 77, the electro-magnet 84 being energized, will not effect 130

- a swinging movement of the electro-magnet, whereby the valve structure 87 will not be operated or rendered inactive for supplying pressure to the train stopping means. The 5 closed circuit for energizing the electro-magnet 84 of the apparatus 41, remains closed until the contact 47 and shoe 45 engage the insulation 26, when the circuit is opened, a second circuit however being closed to again 10 energize the electro-magnet 84 when the contact and contact shoe engages the ramp-section 24^b. In this last named closed circuit current flows from one pole of the source of current 28, through wire 29, ramp-section 15 24^b, contact 47 and shoe 45, wire 85', electro-magnet 84, wire 84', the frame work of the locomotive, traffic rail 16 of block A, and back to the opposite pole of the source of current. The function of having the ramp- 20 section 24^b permanently connected with one pole of the source of current 28, as above stated, is to provide means whereby the train stopping means will not be actuated when the locomotive travels in an opposite direction 25 to the direction of traffic, as when backing, it being disadvantageous for the train stopping means to operate under these conditions. The locomotive or train is thus allowed to pass from block B into block A, 30 without the train stopping means being actuated.
- When the locomotive traveling from block A into block B, approaches the ramps 24 and 25, as above stated, the contact 47 and shoe 35 45 of the apparatus 42 engage the ramp-section 25^a, whereby the reciprocatory bar or element 44 of the apparatus 42 is moved upwardly. This movement of the bar or element 44 is transmitted to the rod 61, which 40 through the medium of fluid pressure operated means including the diaphragms, is transmitted to the rod 71 in apparatus 42, said rod 71 being in turn moved upwardly. Prior to this upward movement of the rod 45 71 the electro-magnet 84 of the apparatus 42 has been energized, whereby the turning movement of the sleeve 76 will not effect a corresponding movement of the sleeve 79 and the valve structure 87 will not be operated to sound the whistle 129. In the closed 50 circuit for energizing the electro-magnet 84 of the apparatus 42, current flows from one pole of the source of current 28, through contact-armature 30, contact 31, wire 32, 55 contact 36', wire 38', ramp-section 25^a, contact 47 and shoe 45 of apparatus 42, wire 85', electro-magnet 84, wire 84', the frame work of the engine, traffic rail 16 of the block A, and back to the opposite pole of 60 the source of current 28. When the contact 47 and shoe 45 engage the insulation 27, the circuit for energizing the electro-magnet 84 is broken, but is again closed when the contact and shoe engage the ramp-section 25^b. 65 In this last named closed circuit current
- flows from one pole of the source of current 28, through wire 29, ramp-section 25^b, contact 47 and shoe 45, of the apparatus 42, wire 85', electro-magnet 84, wire 84', the frame work of the engine, through traffic 70 rail 16 of block A, and back to the opposite pole of the source of current 28. The function of having the ramp-section 25^b permanently connected with one pole of the source of current 28 is to provide means 75 whereby the audible signal or whistle 129 will not be sounded when the locomotive is traveling in an opposite direction to the direction of traffic, as backing up, it being disadvantageous to have the whistle sounded under these conditions. It is thus seen that the locomotive is allowed to enter block B from block A without the signal being operated.
- When the locomotive or train traveling in 80 the block B approaches the entrance end of block C, which is at caution condition, the contact 47 and shoe 45 of apparatus 41 will engage ramp-section 24^a, guarding the entrance end of block C. As the semaphore 85 paddle 36 occupies the intermediate position, the contact blade 37 engages contact 34, whereby the ramp-section 24^a is electrically connected with one pole of the source of current 28. The circuit for energizing 90 the electro-magnet 84, in the apparatus 41, is again closed, whereby the train stopping means will not be actuated, such circuit remaining closed until the contact and contact shoe engage the insulation 26, at which 95 time the circuit is opened as above explained. When the contact 47 and shoe 45 of apparatus 41 engages the ramp-section 24^b the second circuit for energizing the electro-magnet 84 of apparatus 41 is closed, 100 105 as above explained. It is seen that the locomotive or train is allowed to pass from block B into block C without the train stopping means being actuated.
- When the locomotive approaches the 110 ramps 24 and 25 guarding the entrance end of block B, as above stated, the contact 47 and shoe 45 of apparatus 42 engage the ramp-sections 25^a, which now has no electrical connection with the source of current 115 28, as the contact blade 37 is out of engagement with the contact 36'. The shoe 45 and bar or element 44 is accordingly elevated, which movement is transmitted to the rod 71 of apparatus 42, through the medium of 120 the fluid pressure connecting means, whereby the arm 77 is swung upwardly. The sleeves 76 and 79 being now locked together, the electro-magnet 84 is swung to the left, whereby valve structure 87 is actuated, and pressure supplied to the whistle 129, to sound the same through pipe 128. When the contact 47 and shoe 45 of the apparatus 42, engage the ramp-section 25^b, the circuit is 125 closed for energizing the electro-magnet 84 130

as above explained. It is thus seen that the locomotive is allowed to pass from block B into block C but the signal 129 is operated or sounded to apprise the engineer of the caution condition of block C.

5 When the locomotive or train moves into proximity to block D at danger condition, the contact 47 and shoe 45 of apparatus 41 engages the ramp-section 24^a, guarding the entrance end of block D. As block D is at danger condition, the semaphore paddle 36 guarding the entrance end thereof, occupies the lowermost position, and the contact blade 37 is moved out of engagement with all of 10 the contacts 34, 36', and 37', whereby the ramp-section 24^a has no electrical connection with the source of current 28. The electrical connection between the ramp-section 24^a and the source of current 28 is also broken at 15 the contact 31, the electro-magnet being de-energized by the presence of the locomotive or train in the block D. The longitudinal movement of the shoe 45 of apparatus 41 along the ramp-section 24^a causes the up- 20 ward movement of the element or bar 44, whereby the rod 61 is elevated, which movement is transmitted to the rod 71, to move the same upwardly, through the medium of the fluid pressure operated means. The elec- 25 tro-magnet 84 of the apparatus 41 now being deenergized, the sleeves 76 and 79 are locked to turn with each other, whereby the valve structure 87 will be operated, and pressure supplied to the pipe 90. This pressure enters 30 the inlet end of the cylinder 95, swinging the bell-crank lever 101 inwardly. This movement of the bell-crank lever draws the link 105 inwardly, which first unlocks the latch 113, and subsequently moves the throttle lever 106 to its closed position to cut off 35 the supply of steam. The pressure supplied into the pipe 90 also passes into pipe 122, such pressure moving the piston 125, whereby the engineer's air brake valve 127 is 40 moved to its active position for applying the brakes. When the contact 47 and shoe 45 of apparatus 41 engage the ramp-section 24^a, the electro-magnet 84 of such apparatus is again energized, as above described. 45

50 When the contact 47 and shoe 45 of apparatus 42 engages ramp-section 25^a, guarding the entrance end of block D, the whistle 129 will be operated, since the ramp-section 25^a has no electrical connection with the source of current 28. When the contact 47 and shoe 45 of apparatus 42 engages the ramp-section 25^a near the entrance end, of block D, the circuit is again closed to energize the electro-magnet 84 of apparatus 42, as above explained. It is thus seen that the locomotive 55 is stopped and the whistle sounded, when the same travels past the ramps 24 and 25 guarding the entrance end of block D in danger condition.

It is to be understood that the form of 65 my invention herewith shown and described is to be taken as a preferred example of the same and that various changes in the shape, size and arrangement of parts may be resorted to without departing from the spirit 70 of the invention or the scope of the subjoined claims.

Having thus described my invention, I claim:—

1. In a train control system of the character described, a pair of relatively movable elements to be carried by the vehicle, electrically operated means adapted when de-energized to lock the elements for movement together in one direction and when energized 80 to unlock them, train stopping means connected with one element, a fluid pressure operated device connected with the other element to move it, apparatus for supplying fluid pressure into the pressure operated device, a vertically movable shoe for operating the apparatus, a ramp disposed in the path of travel of the shoe to move it, means electrically connecting the shoe with the electrically operated means, a source of current, 90 and means connecting and disconnecting the ramp with and from the source of current.

2. In a train control system of the character described, a conduit containing a fluid to be compressed, train stopping means embodying a movable element arranged near one end of the conduit to be actuated by the compressed fluid therein, electrically operated means adapted to render the train stopping means operative and inoperative, a movable element arranged near the opposite end of the conduit and adapted when moved in one direction to compress the fluid therein, a movable shoe having connection with the second named movable element, a ramp disposed in the path of travel of each shoe, a source of current, and means for connecting and disconnecting the ramp with and from the source of current.

3. In a train control system of the character described, a track, a vehicle to travel thereon, vehicle stopping means mounted upon the vehicle, signaling means mounted upon the vehicle, mechanically operated apparatus to actuate the vehicle stopping means, electrically operated means to render the mechanically operated apparatus operative and inoperative with respect to fulfilling its function and electrically connected with the mechanically operated apparatus, 115 independently operating mechanically operated apparatus to actuate the signaling means, electrically operated means for rendering the second named mechanically operated apparatus operative and inoperative 120 with respect to actuating the signaling means and electrically connected with the second named mechanically operated appa-

ratus, ramps disposed in the path of travel of the mechanically operated apparatuses to move them, and means to alternately connect and disconnect the ramps with and from the source of current.

4. In a train control system of the character described, a track, a vehicle to travel thereon, vehicle stopping means mounted upon the vehicle, signaling means mounted 10 upon the vehicle, mechanically operated apparatus to actuate the vehicle stopping means, independently operating mechanically operated apparatus to actuate the signaling means, ramps disposed in the path of 15 travel of the mechanically operated apparatuses to move them, electrically operated means to control the operation of the vehicle stopping means and signaling means by the mechanically operated apparatuses, and 20 means to alternately connect the ramps with the source of current.

5. In a train control system of the character described, a track, a vehicle to travel thereon, mechanically operated and electrically controlled vehicle stopping means mounted upon the vehicle, independently operating mechanically operated and electrically controlled signaling means mounted 25 upon the vehicle, a corresponding number of 30 separate ramps disposed in the path of travel of the vehicle stopping means and signaling means, to operate the same, and means for

alternately connecting the ramps with a source of current.

6. In a train control system of the character described, mechanically operated apparatus embodying a shoe, a ramp to engage the shoe to move the same, and a contact member pivoted to the shoe and adapted to engage with the ramp. 35 40

7. In a train control system of the character described, mechanically operated apparatus embodying a shoe, a ramp to engage the shoe to move the same, a contact member pivoted to the shoe and adapted to engage with the ramp, and a spring to force 45 the pivoted contact member outwardly with relation to the shoe.

8. In a train control system of the character described, mechanically operated apparatus embodying a shoe having a recess formed through the engaging face thereof, a ramp to engage the face of the shoe to move the same, a contact member movably mounted within the recess and adapted to 50 engage with the ramp, and a spring to move the contact member outwardly with relation to the recess. 55

In testimony whereof I affix my signature in presence of two witnesses.

WILLIAM B. MURRAY.
